UNITED STATES PATENT OFFICE.

JAMES O. HEADRICK, OF HUMBLE, TEXAS.

BREAK-OUT PIN.

1,319,335.

Specification of Letters Patent.

Patented Oct. 21, 1919.

Application filed July 14, 1919. Serial No. 310,829.

To all whom it may concern:

Be it known that I, JAMES O. HEADRICK, a citizen of the United States, residing at Humble, Harris county, Texas, have invented a certain new and useful Improvement in Break-Out Pins, of which the following is a full, clear, and exact description, such as will enable others skilled in the art to which it appertains to make and use the same.

My invention relates to an improvement in break-out pins to be used in connection with the drilling rotary on the derrick platform, in the operation of screwing and unscrewing pipe in well drilling.

In the drilling of wells, in earth for oil, water, gas, etc., it is customary to raise the pipe to be unscrewed slightly above the derrick platform so that the joint may be gripped by a pipe wrench or tongs of ordinary construction to hold the same stationary. Another wrench is then placed upon the pipe above the joint and is used to unscrew the upper section of pipe from the joint below. In this operation, the lower wrench, after it has been engaged upon the pipe joint, is allowed to swing around until the handle of the wrench comes in contact with a break-out pin, which is placed within a hole in the rotary or platform in some pre-arranged position. The break-out pin ordinarily used is a straight bar of iron or some other rigid material. The contact of the wrench handle with the break-out pin serves to prevent further rotation of the wrench so that the pipe joint will be held stationary. The operation of the other wrench upon the section of pipe above will serve to force the handle of the lower wrench tightly against the upper end of the break-out pin. The contact of the wrench handle with the pin will prevent the rotation of the pipe so that the operation of the other wrench will serve to unscrew or break the joint of pipe so that the length of pipe above may be removed. The difficulty usually experienced with the ordinary type of break-out pin is that when the joint of pipe has been broken it is very difficult to release the wrench which is held in tight contact with the break-out pin. The wrench is usually locked rather securely upon the pipe and as it is held tightly against the pin it is difficult to remove the pin without first releasing the wrench.

An object of my invention is to provide a break-out pin which will allow the handle of the wrench to swing past the pin and be thus easily released from the pipe when so desired, but which will be so constructed as to maintain a rigid support to prevent the rotation of the wrench during the break-out operation.

Other objects will more clearly appear in the description which follows, and will also be pointed out with particularity in the claims.

Referring to the drawing forming a part of this specification, and wherein like parts are designated by like numerals of reference throughout the several views, Figure 1 is a side elevation of the upper end of my improved break-out pin showing the upper end thereof in its open position, some parts being broken away for greater clearness; Fig. 2 is a side elevation taken at right angles to the view shown in Fig. 1 illustrating the break-out pin in its closed or operative position; Fig. 3 is a view similar to that shown in Fig. 1 illustrating a slightly different embodiment of my invention; Fig. 4 is a view similar to that shown in Fig. 3 illustrating the break-out pin in closed position.

My improved break-out pin consists of a lower supporting post 1, which is shown in Fig. 2 as being seated rotatably within an opening in the platform 2 of a rotary, the opening in the rotary being surrounded by an upwardly extending collar or flange 3 for better support for the said post. It is understood, of course, that in ordinary practice holes are usually bored in the base of the rotary or in the platform, and the collar or flange 3 may be used or not as found best. The post 1 is rotatable within the collar 3 and is provided with a lateral groove 4 adjacent the upper end thereof, said groove providing a seat into which the upper pivoted stop member 5 is seated. This groove is open at one side and the stop pin 5 is pivoted upon a pin 6 adjacent the lower end thereof in such manner that it may be thrown into horizontal position, as shown in Fig. 1, and when in this position a forward rounded face 7 thereof will contact with the shoulder 8 provided at the lower end of the groove 4. The rearward side 15 of the groove at the upper end of the post 1 constitutes a stop to limit the movement of the

pin 5 in one direction. The upper walls of the slot 4 may be beveled or tapered backward to the upper wall of the slot as shown at 9. At the upper end of the pivoted stop pin 5, I prefer to fix a handle 10 which is preferably a round pin threaded at one end and adapted to fit within an opening in the upper end of the pin 5 and held securely in place by nuts 11 on either side of the said pin.

Fig. 2 shows the break-out pin in operative position, and also illustrates it as being in contact with the handle or lever arm of a wrench 13, in gripping contact with the joint 14 of a string of pipe. In this position it will be noted that the contact of the wrench arm with the stop pin will prevent the rotation or swinging of the wrench handle beyond the pin. When the joint has been broken the operator will grasp the handle 10 of the break-out pin and turn the pin within the support 2 at an angle of 90° from the position shown. This rotation of the pin is facilitated by the rounding of the stop pin 5, as shown at 7. When the break-out pin is in that position it can then be thrown down into open position, as shown in Fig. 1, and the handle of the wrench may then be swung around and the wrench detached from the pipe.

In Figs. 3 and 4, I have illustrated a slightly different embodiment of my invention. In this embodiment the post 1' is provided with a groove 4' in the upper end similar to that shown in Fig. 1, except that the rear wall 15 is provided with an opening or slot 16 at the lower end thereof on the opposite side from the groove 4'. Also the lower end of the groove 4' is beveled backwardly at 18 toward the lower end of the slot 16, and the stop pin 5' is also beveled at 17 on the lower end thereof to contact with the beveled portion 18 just described. The upper end of the pin 5' may be, if desired, provided with transverse notches or corrugations 19 for the purpose of furnishing a better seat or support for the handle of the wrench which will be adapted to seat therein.

In this modification the pin in its erect or closed position, as shown in Fig. 4, will come into contact with the upper wall 15 of the groove 4', and the lower beveled face 17 will also be limited by contact with the beveled face 18 of the groove 4'. When the pin is thrown into open position to allow the wrench to be released, the lower end of the stop pin 5' will contact with the upper wall of the slot 16 and prevent the stop pin 5' from falling beyond the horizontal position shown in Fig. 3.

The purpose of my invention will now be clearly understood as it will be obvious that the pin may be broken at the central point by simply turning the post within its open-

ing in the platform and throwing the pin down to a point below the handle of the wrench, and then the wrench may be easily swung around and released. Much time will be saved by means of this form of break-out pin and it will also prevent the breakage usually occurring when the wrench and the break-out pin are pounded or hammered to release the tools from the pipe. For by the use of my break-out pin no hammering or pounding of the parts will be necessary. The break-out pin will simply be rotated and swung down out of the path of the handle of the wrench and the wrench easily released by swinging the handle a little farther and loosening the jaws of the same.

Having thus described my invention, the objects and advantages of which will be clear without further description, what I claim as new and desire to protect by Letters Patent is:

1. In a break-out pin, a supporting post, the upper end thereof being provided with a lateral groove, a stop pin pivoted at its lower end in said groove, and a handle at the upper end of said pin.

2. In a break-out pin, a supporting post mounted rotatably in a supporting platform, a lateral groove in the upper end thereof, a stop pin pivoted in the lower end of said groove, and adapted to contact with the rear wall of said groove in the manner described.

3. In a break-out pin, a supporting post, a stop pin pivoted adjacent the upper end thereof, means to prevent the swinging of said pin beyond a vertical position in one direction, and means to prevent the swinging of said pin in the opposite direction beyond a horizontal position.

4. In a break-out pin, a platform, a supporting post mounted rotatably therein, a stop pin pivoted adjacent the upper end of said post, the outer face of said pin being rounded, means to prevent the swinging of said pin beyond a vertical position in one direction and means to prevent its swinging beyond a horizontal position in the opposite direction.

5. In a break-out pin, a supporting post, a groove in the upper end thereof, a slot in the lower end of said groove opening in the opposite direction from said groove, a stop pin pivoted toward the lower end of said groove, said stop pin being rounded on the forward face thereof and provided with notches near the upper end thereof.

6. In a break-out pin, a supporting post rotatably mounted in an opening in a support, the upper end of said pin being provided with a groove on the forward side thereof, a slot in the lower end of said groove on the rearward side thereof, a stop pin pivoted in said groove, the rearward wall of said groove adapted to prevent the

swinging of said pin in a rearward direction, the upper wall of said slot adapted to prevent the movement of said pin in a forward direction beyond a horizontal position, 5 and a handle at the upper end of said pin.

7. In a break-out pin, a rotatable supporting post, a stop pin pivoted adjacent the

upper end of said post, means to prevent the swinging of said pin on said post beyond a vertical position in one direction. 10

In testimony whereof, I hereunto affix my signature this the 8th day of July, A. D. 1919.

JAMES O. HEADRICK.
